Application March 23, 1942, Serial No. 435,813

11 Claims. (Cl. 237—2)

1

This invention relates to heating apparatus and has particular relation to a new and improved type of apparatus comprising a chimney furnace with provisions in the bottom thereof for independently burning a plurality of different kinds of fuel.

A principal object of the invention is to provide a novel and improved type of heating system for supplying heated air to a space in a building to be occupied by and for the comfort of human beings comprising a chimney which forms a part of the building and which extends upright to and above the roof of the building and has an atmospheric discharge external of the space, a combustion chamber in the lower portion of the chimney constructed and arranged for burning a plurality of different kinds of fuel under natural draft operation, and a heat exchanger within and extending along a substantial portion of the length of the chimney and providing a means for efficiently transferring heat from the combustion products to air which is delivered to the space to be heated for heating the same.

Another object of the invention is to provide a heating system of the character described with a combustion chamber which is constructed and arranged normally to burn one kind of fuel, said combustion chamber being provided with means for burning a different kind of fuel which may be operated simultaneously with or independently of the normal fuel burning means.

Another object of the invention is to provide a heating system with a combustion chamber adapted to burn either gas or oil fuel under natural draft operation together with means for burning hard fuel either independently of or simultaneously with the operation of the gas or oil burning means and which hard fuel burning means are adapted to function as an incinerator for disposing of rubbish.

Other objects and advantages of the invention will be apparent from a consideration of the following specification taken in conjunction with the accompanying drawings, of which there are two sheets and wherein:

Figure 1 is a vertical cross section through a part of a house illustrating one form of heating system embodying the invention and the method of circulating the air to be heated through the heating system and through the house;

Fig. 2 is an enlarged elevational view of part of the heating system illustrated in Fig. 1 with certain parts broken away;

Fig. 3 is an enlarged vertical sectional view through the combustion chamber and the lower

2

part of the heat exchanger of the system illustrated in Fig. 2;

Fig. 4 is a sectional view with parts shown in elevation taken along the staggered line 4—4 of Fig. 2, looking in the direction of the arrows;

Fig. 5 is a horizontal sectional view taken along the line 5—5 of Fig. 4;

Fig. 6 is a horizontal sectional view taken along the line 6—6 of Fig. 3 and illustrating certain details of the combustion chamber; and

Fig. 7 is a diagram of a control circuit for the air blower of the heating system.

As illustrated in the embodiment of the invention selected for purposes of illustration, a heating system embodying my invention comprises in general and as illustrated in Figs. 1, 2 and 3, a chimney 10 which forms part of the building indicated generally at 12 and which extends upright to and above the roof 14 of the building and has an atmospheric discharge 16 external of the space 18 in the building 12 to be heated. A combustion chamber indicated generally at 20 is formed in the lower portion of the chimney 10 and is constructed and arranged for burning fuel under natural draft operation. The chimney 10 may be of conventional masonry construction and of rectangular cross section as illustrated, and is provided with a heat exchanger indicated generally at 22, said heat exchanger being within and extending along a substantial portion of the length of the chimney 10 and providing a path 24 for the flow of the products of combustion and a separate path 26 for the flow of air in intimate heat exchange relationship with the path for flow of the combustion products upwardly through said combustion products path 24.

Means are provided outside of said chimney 10 to supply from the space 18 to the upper portion of the air path 26 air to be heated under a pressure greater than the pressure of the products of combustion, and such means comprise an air moving device or blower 28 arranged to be driven by an electric motor 30, a conduit indicated generally at 32 leading through the attic space 34 of the building, one end of the conduit being connected to the intake side of the blower 28 and the other end of the conduit 32 communicating with return air openings 36 communicating with the space 18 to be heated. The chimney 10 is provided with one or more outlet openings 38 leading from the lower end of the air path 26 and adapted for discharging heated air into the space 18.

The combustion chamber 20 is arranged in the lower part of the chimney and is defined at least

in part by the walls thereof. The chamber 20, as illustrated more particularly in Figs. 3 and 6, is divided into two parts 42 and 44 by the transverse vertical partition 40, the upper end of which as illustrated terminates below the upper end of the combustion chamber 20. The lower part of the chimney 10, it will be observed, is wider or of greater cross section than the upper part thereof in order to provide space for the combustion chamber portions 42 and 44.

The combustion chamber part or portion 42 may as illustrated have operatively associated therewith a fluid fuel burning means such as a pot or heat vaporizing type of burner indicated generally at 46 to which oil from a reservoir (not shown) is supplied under the control of an oil control valve 48 which may be provided with a manual control 50 by means of which the rate of flow of oil to the burner 46 may be regulated.

The burner 46 comprises an atmospheric or heat vaporizing type of burner and includes a pot provided with suitable air openings thereinto for supplying air to the burner and the combustion chamber so as to provide a combustible mixture of fuel and air and to support combustion. The pot burner includes a plate 52 extending transversely of the chamber portion 42 and supported by the walls thereof. The plate 52 has an opening therein above the pot so as to permit the combustion of the oil vapors within the combustion chamber 42. The pot 46 may be supported by the plate 52 and an air intake opening 54 is provided in the wall of the chimney below the burner 46 for supplying air thereto. A suitable door 56 may be provided in the wall of the combustion chamber 42 for obtaining access thereto in order to light the burner 46 which may be accomplished by throwing a lighted flare into the pot 46 when there is oil therein.

The valve 48 may be set to control the supply of oil to the burner 46 so as to produce a pilot flame or to produce a high flame or a flame intermediate the high flame and the pilot flame, depending upon the position of the control handle 50. The products of combustion resulting from the operation of the burner 46 are supplied under natural draft to the flue or combustion products path 24.

The combustion chamber 44 is constructed and arranged for burning a hard fuel such as coal or wood and is also adapted for functioning as an incinerator to burn combustible rubbish. To this end the chamber 44 is provided with grates 58 for supporting the fuel to be burned. Access to the chamber 44 is provided by a fuel door 60 carried by a metallic wall 62 which closes one side of the chamber 44. The wall 62 may also be provided with an ash removal door 64 having a damper controlled air inlet opening 66 for admitting air to the combustion chamber 44 below the grates 58 for supporting combustion in the chamber 44.

If desired the walls of the chimney 10 which define the combustion chambers 42 and 44 each of which forms a part of the combustion chamber 20 may be formed of insulating brick so as to reduce the heat transfer through the walls thereof.

The heat exchanger 22 comprises as illustrated an elongated tubular member or pipe composed of a series of lengths of stove pipe arranged in end to end relationship and a foot 68, the walls of which foot 68 may be formed of metal of substantially greater thickness than the walls of the lengths of pipe used to provide the heat ex-

changer thereabove. The foot 68 is provided with a laterally extending continuous flange 70 which is adapted to seat on and be supported by a suitable ledge formed internally of the chimney 10 at the upper end of the combustion chamber 20. The heat exchanger 22 separates the combustion chamber from the space thereabove and surrounding the heat exchanger 22 and cooperates with the chimney to provide the path 24 for the products of combustion and the path 26 for the air to be heated.

The upper end of the air path 26 is closed by a transverse plate 72 through which the upper end of the heat exchanger 22 extends and which plate 72 functions to separate the flue path 24 thereabove from the air path 26. The foot 68 supports the pipe sections which comprise the heat exchanger 22 and in turn is supported by the side walls of the chimney 10. The blower 28 may be mounted on a plate 74 secured to the upper portion of the chimney 10 and have its discharge 76 arranged to deliver air through an opening 78 formed in the chimney wall 10 and adjacent the upper end of the heat exchanger 22 and below the plate 72. As the air discharged by the blower 28 into the air path or duct 26 is under a pressure greater than the pressure of the products of combustion in the path or duct 24, any leakage of the heat exchanger 22 will not contaminate the air path but will merely permit leakage of air into the flue 24.

The motor 30 which drives the blower 28 may be arranged in a circuit 80 controlled by a thermostatic switch 82, said thermostatic switch 82 being mounted on the chimney wall and having the thermal element 84 thereof arranged in the flue 24 immediately above the upper end of the exchanger 22 so as to be responsive to the temperature of the products of combustion as the same leave the heat exchanger 22. The switch 82 may be set to close the motor circuit when the flue gas temperature reaches a certain degree, say, for example, 225° F., and to break the motor circuit when the flue gas temperature drops below a certain degree, say, for example, 200° F. The control circuit is diagrammatically illustrated in Fig. 7.

As illustrated in Fig. 3, the foot 68 may be formed internally to provide a series of spiral vanes or baffles 86 which serve to impart a whirling motion to the products of combustion as they pass upwardly through the flue 24 and thereby expedite heat exchange with the air which flows through the path 26. Below the vanes 86 a draft restricting device comprising a damper 88 of materially less cross sectional area than the cross sectional area of the path 24 may be arranged, the damper 88 being pivotally mounted on suitable trunnions which are journaled in the wall of the foot 68, and one of the trunnions may be extended through the wall of the chimney 10 and provided with a handle 90 so as to permit adjustment of the damper 88 thereby to vary the effective draft within the combustion chamber 20. The draft restricting device is provided so as to restrict the effective draft within the combustion chamber 20 to that which is desirable to efficiently burn fuel therein and so as to prevent the passage through the combustion chamber 20 and the flue path 24 of large amounts of air which are not necessary to support combustion.

The air discharged into the upper end of the air path 26 by the blower 28 flows downwardly in the unidirectional path provided between the heat exchanger 22 and the inside of the chimney 10

and is discharged through the openings or outlets 38 formed in the chimney walls 10 at the lower end of the air path 26.

The air conduit 32 for supplying air from the space 18 to be heated to the intake side of the blower 28 comprises a T-pipe 94, a pipe 96 connecting the T-pipe 94 with a header duct 98 and one or more ducts such as 100 formed between the ceiling joists and one end of which communicates with the header duct 98 and the other end of which communicates with the upper end of a duct 102 formed between the studding of the house, the lower end of the duct 102 communicating with the air returns 36. During operation of the blower 28 air is withdrawn from the space 18 through the outlets 36, ducts 102, 100, 98 and 96, and pipe 94 is forced by the blower 28 under pressure into the air path 26 and in heat exchange relationship with the exchanger 22 and thence discharged through the openings 38 into the space to be heated. As illustrated in Figs. 1, 2 and 3, one of the openings 38 may communicate with the lower end of a duct 106 which extends vertically and which is arranged along the outside of the chimney 10. The duct 106 may extend upwardly to the space between the ceiling joists and then laterally to a distant part of the house for supplying heated air thereto.

The chimney 10 as illustrated in Fig. 1 is supported upon a footing 110 just below the floor of the space 18 and at least some of the outlets 38 are arranged so as to discharge heated air laterally just above the floor of the space 18. If desired, the chimney may be concealed by finished walls extending therearound within the space 18.

The fuel burning means associated with the chamber 42 is adapted to operate independently of the fuel burning means associated with the chamber 44 and vice versa. In operation either or both fuel burning means are adapted to supply heated products of combustion to the interior of the heat exchanger 22 for the purpose of heating the same and when the temperature of the flue 24 at the upper end of the exchanger 22 reaches a temperature of, say for example, 225° F., the switch 82 will close the motor circuit 80 and cause the blower 28 to circulate air to be heated through the path 26 and into the space 18. The supply of fuel to the fuel burning means associated with both the chambers 42 and 44 is manually controlled although it may be automatically controlled in accordance with the disclosure of Patent 2,348,834 issued to me on May 16, 1944, for "Heating apparatus," and reference to which is hereby made for the details of controls and other embodiments of certain particulars herein illustrated. When the fuel supply to either or both of the fuel burning means associated with the chambers 42 and 44 is reduced to a point at which the temperature of the flue gases leaving the upper end of the heat exchanger 22 is below approximately 200° F., the switch 82 will open and discontinue operation of the blower 28.

In the event of current failure during the time that heated products of combustion are being supplied to the flue 24 from either or both of the fuel burning means and when the blower 28 is operating, a means for dissipating heat from the system is provided and comprises a damper controlled vent 112 provided by the end of the T-pipe 94 remote from the blower 28 as shown in Fig. 1. A weighted damper 114 is arranged to occupy the

position illustrated in Fig. 1 when the blower 28 is at rest thereby venting the air path 26 to the attic space 34. However, when the blower 28 is operating, the suction effect of the blower 28 will draw the damper 114 to a position to close the vent 112 and thereby will draw air from the space 18 to be heated as previously described.

The structure herein disclosed and claimed constitutes an improvement upon that disclosed in my application Serial No. 399,780, filed June 26, 1941, for "Heating apparatus," now Patent No. 2,274,341, issued February 24, 1942, and I contemplate that the various types of heat exchangers illustrated therein may be used in the structure herein disclosed in place of the specific type of heat exchanger herein illustrated.

In lieu of the specific types of fuel burning means illustrated herein, other types or kinds of fuel burning means may be employed, such, for example, as those disclosed in my prior applications hereinbefore referred to. In using the phrase "different types of fuel" in the claims, I mean, for example, that a hard fuel such as coal or wood is of a different type than a fluid fuel such as gas or a liquid fuel.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. A heating system for supplying heated air to a space in a building to be occupied by and for the comfort of human beings comprising a chimney which forms part of the building and which extends upright to and above the roof of the building and has an atmospheric discharge external of the space, a plurality of combustion chambers in the lower portion of said chimney, means associated with each of said combustion chambers and constructed and arranged for burning fuel and functioning to supply heated products of combustion to said chimney, one of said means being adapted to burn a different kind of fuel than the other, a heat exchanger member extending longitudinally of and for a substantial portion of the length of said chimney and providing a path for the flow of the products of combustion and a separate path for flow of air in intimate heat exchange relationship with the combustion products, an outlet from the lower end of said air path into said space, and means including an air moving device operable to supply to the upper portion of said air path, air to be heated and under a pressure greater than the pressure of the products of combustion.

2. A heating system for supplying heated air to a space in a building to be occupied by and for the comfort of human beings comprising a chimney which forms part of the building and which extends upright to and above the roof of the building and has an atmospheric discharge external of the space, a plurality of combustion chambers in the lower portion of said chimney, means associated with each of said combustion chambers and constructed and arranged for burning fuel and functioning to supply heated products of combustion to said chimney, one of said means being adapted to burn a different kind of fuel than the other, a heat exchanger member extending longitudinally of and for a substantial

portion of the length of said chimney and providing a path for the flow of the products of combustion and a separate path for flow of air in intimate heat exchange relationship with the combustion products, an outlet from the lower end of said air path into said space, means including an air moving device operable to supply to the upper portion of said air path, air to be heated and under a pressure greater than the pressure of the products of combustion, and means for dissipating heat from the heat exchanger member if the air moving device fails to operate when at least one of said fuel burning means are generating heated products of combustion.

3. A heating system for supplying heated air to a space in a building to be occupied by and for the comfort of human beings comprising a chimney which forms part of the building and which extends upright to and above the roof of the building and has an atmospheric discharge external of the space, a plurality of combustion chambers in the lower portion of said chimney, means associated with each of said combustion chambers and constructed and arranged for burning fuel and functioning to supply heated products of combustion to said chimney, one of said means being adapted to burn a different kind of fuel than the other, a heat exchanger member extending longitudinally of and for a substantial portion of the length of said chimney and providing a path for the flow of the products of combustion and a separate path for flow of air in intimate heat exchange relationship with the combustion products, an outlet from the lower end of said air path into said space, means including an air moving device operable to supply to the upper portion of said air path, air to be heated and under a pressure greater than the pressure of the products of combustion, means operable in response to an increase in temperature in the chimney above a predetermined point for operating said air moving device, and for discontinuing the operation of said air moving device in response to a decrease in temperature in the chimney below a predetermined point, and a damper controlled vent at the upper end of said air path adapted to vent said air path under predetermined conditions, said damper controlled vent being closed by the operation of said air moving device.

4. A heating system for supplying heated air to a space in a building to be occupied by and for the comfort of human beings comprising a chimney which forms part of the building and which extends upright to and above the roof of the building and has an atmospheric discharge external of the space, a plurality of combustion chambers in the lower portion of said chimney, means associated with each of said combustion chambers and constructed and arranged for burning fuel and functioning to supply heated products of combustion to said chimney, each of said fuel burning means being operable independently of or simultaneously with the other, one of said means being adapted to burn a different kind of fuel than the other, a heat exchanger member extending longitudinally of and for a substantial portion of the length of said chimney and providing a path for flow of the products of combustion and a path for flow of air in intimate heat exchange relationship with the combustion products, an outlet from the lower end of said air path into said space, means including an air moving device operable to supply to the upper portion

5 of said air path, air to be heated and under a pressure greater than the pressure of the products of combustion, an electrically operated source of power for operating said air moving device, and an electric circuit therefor including a thermostatic switch responsive to heat generated by either or both of said fuel burning means.

10 5. A heating system for supplying heated air to a space in a building to be occupied by and for the comfort of human beings comprising a chimney which forms a part of the building and which extends upright to and above the roof of the building and has an atmospheric discharge external of the space, a combustion chamber in the lower portion of said chimney, a heat exchanger member extending longitudinally of and along a substantial portion of the length of said chimney and providing a path for flow of the combustion products and a separate path for flow of air in intimate heat exchange relationship with the path for flow of the combustion products, an outlet from one end of said air path discharging into said space, means including an air moving device operable to supply to the other end of said air path, air to be heated and under a pressure greater than the pressure of the products of combustion, fuel burning means associated with said combustion chamber and constructed and arranged for burning fuel and functioning to supply heated products of combustion to said combustion products path, each of said fuel burning means being operable independently of or simultaneously with the other.

15 20 30 35 40 45 50 55 60 65 70 75 8. 6. A heating system for supplying heated air to a space in a building to be occupied by and for the comfort of human beings comprising a chimney which forms a part of the building and which extends upright to and above the roof of the building and has an atmospheric discharge external of the space, said chimney being constructed so as to produce a high potential draft, a combustion chamber in the lower portion of said chimney, fuel burning means associated with said combustion chamber and constructed and arranged for burning fuel under natural draft operation and functioning to supply heated products of combustion to said chimney, a heat exchanger member extending longitudinally of and along a substantial portion of the length of said chimney and providing a path for the flow of the products of combustion and a separate path for flow of air in intimate heat exchange relationship with the path for flow of the combustion products, openings at the lower and upper ends of said air path communicating with said space, means to supply from said space to one of said openings, air to be heated and under a pressure greater than the pressure of the products of combustion, the opening at the other end of said air path forming an outlet for discharging heated air into said space, a draft restricting device in said chimney for restricting the effective draft in the combustion chamber to that required for efficiently burning fuel therein and which will prevent the passage through the combustion chamber and chimney of large amounts of air which are not necessary to support combustion, and other fuel burning means associated with said combustion chamber and operable independently of said first-mentioned fuel burning means to

supply heated products of combustion to said chimney.

7. A heating system for supplying heated air to a space in a building to be occupied by and for the comfort of human beings comprising a chimney which forms a part of the building and which extends upright to and above the roof of the building and has an atmospheric discharge external of the space, said chimney being enlarged at its base, a combustion chamber in the enlarged portion of said chimney, a plurality of fuel burning means associated with said combustion chamber and constructed and arranged for burning fuel under natural draft operation and functioning to supply heated products of combustion to said chimney, a heat exchanger member extending longitudinally of and along a substantial portion of the length of said chimney and providing a path for the flow of the products of combustion and to which path the products of combustion from said fuel burning means are supplied at combustion temperature and a single separate unidirectional path for flow of air in intimate heat exchange relationship with the path for flow of the combustion products and through which path all of the air to be heated must pass, an outlet from the lower end of said air path discharging into said space, means including an air moving device to supply from said space to the upper end of said air path, air to be heated and under a pressure greater than the pressure of the products of combustion, each of said fuel burning means being operable independently of the other or simultaneously therewith without interfering with the efficient generation of heated products of combustion by the other, said fuel burning means and combustion chamber being arranged at substantially the same elevation and below the lower end of said heat exchanger member, an electrically operated source of power for operating said air moving device, and an electric circuit therefor including a thermostatic switch responsive to heat generated by either or both of said fuel burning means.

8. A heating system for supplying heated air to a space in a building to be occupied by and for the comfort of human beings comprising a chimney which forms an integral part of the structure of the building and which extends upright to and above the roof of the building and has an atmospheric discharge external of the space, a combustion chamber in the lower portion of said chimney, a plurality of fuel burning means associated with said combustion chamber and constructed and arranged for burning fuel and each of which is adapted to burn a different kind of fuel and to supply heated products of combustion to said chimney independently of the other, a heat exchanger member extending longitudinally of and for a substantial portion of the length of said chimney and providing a path for the flow of the products of combustion and a separate unidirectional path for flow of air in intimate heat exchange relationship with the combustion products, an outlet from one end of said air path discharging into said space, means, including an air moving device, operable to supply from said space to the other end of said air path, air to be heated and under a pressure greater than the pressure of the products of combustion, a relief damper at the upper end of said air path movable to open position, upon stoppage of said air moving device for venting said air path, an electrically operated source of power for operating said air moving device, and an electric circuit therefor including

a thermostatic switch responsive to heat generated by either of said fuel burning means, said damper being closed in response to the operation of said air moving device.

5 9. A heating system for supplying heated air to a space in a building to be occupied by and for the comfort of human beings comprising a chimney which forms an integral part of the structure of the building and which extends upright to and above the roof of the building and has an atmospheric discharge external of the space, the lower portion of said chimney being enlarged and formed to provide a plurality of combustion chambers, each of said combustion chambers having 10 fuel burning means constructed and arranged for burning fuel and functioning to supply heated products of combustion to said chimney, each of said fuel burning means being independent of the other and being adapted to burn a different kind of fuel, a heat exchanger member extending longitudinally of and for a substantial portion of the length of said chimney and providing a path for the flow of the products of combustion and a separate unidirectional path for flow of air 15 in intimate heat exchange relationship with the combustion products, an outlet from one end of said air path discharging into said space, means, including an air moving device, operable to supply from said space to the other end of said air path, air to be heated and under a pressure greater than the pressure of the products of combustion, and means operable in response to an increase in temperature in the chimney above a predetermined point for operating said air moving device, and for discontinuing the operation of said air moving device in response to a decrease in temperature in the chimney below a predetermined point.

20 10. A heating system for supplying heated air to a space in a building to be occupied by and for the comfort of human beings comprising a furnace having a plurality of fuel burning means, and means for transferring heat generated by either or both of said fuel burning means to air 25 from said space to be heated comprising a common heat exchanger to which products of combustion from either or both of said fuel burning means are supplied, means including an air moving device for circulating air from said space over said heat exchanger and back to said space, and means for dissipating heat from said heat exchanger if said air moving device is not operating when at least one of said fuel burning means are generating heated products of combustion.

30 11. A heating system for supplying heated air to a space in a building to be occupied by and for the comfort of human beings comprising a chimney which forms a part of the building and which extends upright to and above the roof of the building and has an atmospheric discharge external of the space, a heat exchanger member extending longitudinally of and along a substantial portion of the length of said chimney and providing a path for flow of combustion products and a separate 35 path for flow of air in intimate countercurrent heat exchange relationship with the path for flow of combustion products, fuel burning means operable for burning fuel and functioning to supply heated products of combustion to the lower end of said combustion products path at the bottom of said heat exchanger member, other fuel burning means constructed and arranged for burning fuel and functioning to supply heated products of 40 combustion to the lower end of said combustion

11

products path at the lower end of said heat exchanger member, each of said fuel burning means being operable independently of or simultaneously with the other, an outlet from the lower end of said air path discharging into said space, means including an air moving device operable to supply to the other end of said air path air to be heated

12

and under a pressure greater than the pressure of the products of combustion, and means for dissipating heat from the heat exchanger member when said air moving device is not operating when at least one of said fuel burning means is generating heated products of combustion.

MORITZ L. MUELLER.
